SHOE AND THE MANUFACTURE THEREOF

Frank R. Merritt, Haverhill, Mass., assignor to
United Shoe Machinery Corporation, Paterson,
N. J., a corporation of New Jersey

Application November 27, 1931, Serial No. 577,426

7 Claims. (Cl. 12—142)

This invention relates to improvements in the manufacture of shoes and is herein illustrated with special reference to its applicability to the manufacture of shoes having cement-attached 5 outsoles.

It is an object of my invention to provide shoes having a simple and neat but attractive ornamentation. As illustrated herein such ornamentation comprises a stripe on the marginal portion 10 of the sole adjacent to the shoe upper and of a color or material contrasting with the material of the shoe upper. Such a stripe may be simply and effectively produced, in accordance with my invention, by securing a strip of celluloid to the sole before the sole is attached to the shoe, the strip extending peripherally of the sole at its attaching face.

In the manufacture of shoes having cement-attached soles it is customary to roughen the 20 marginal portion of the attaching face of the sole and then to coat the roughened area with pyroxylin cement. As a result of this roughening, difficulty is met with in finishing the marginal portion of the upper-engaging surface of the sole which extends in the finished shoe somewhat beyond the shoe upper. This difficulty has substantially limited this type of work to shoes having very closely trimmed soles. The present 25 invention overcomes this difficulty since the roughened marginal portion of the sole is overlaid with a strip of smooth material, illustrated as celluloid, which, for this purpose, need not be of a color contrasting with the material of the shoe upper.

My invention in its method aspects comprises 30 an improved method of manufacturing shoes and an improved method of preparing soles for attachment to shoes. In other aspects it comprises an improved shoe, and an improved outsole for 35 a shoe.

With the above and other objects and features in view the invention will now be described with reference to the accompanying drawing and pointed out in the claims.

40 In the drawing,

Fig. 1 is a plan view of an outsole prepared in accordance with my invention;

Fig. 2 is a plan view of a strip of celluloid died out for attachment to the sole, as shown in Fig. 1;

Fig. 3 is a transverse section of the sole on the line III—III of Fig. 1; and

Fig. 4 is a perspective view of a shoe embodying my invention.

In manufacturing shoes in accordance with my 55 invention as herein illustrated, the outsole 10

is died out or otherwise cut to approximately its final form, being left, however, slightly larger than the size to which it is to be finished so as to allow for the removal of a small amount of stock in the usual edge trimming operation. 60 The sole 10 is roughened at its attaching surface over an area three quarters of an inch wide, more or less, and extending from somewhat rearwardly of the heel breast line forwardly about the toe of the shoe and back to the heel breast line on the other side, the rearmost part of the roughening being indicated at 12 in Fig. 1. A strip of celluloid 14, illustrated in Fig. 2, is prepared, for example by dieing it out from sheet celluloid, and is secured to the attaching surface 65 of the sole 10 as shown in Figs. 1 and 3. As illustrated herein, this strip extends about the forepart of the sole at and adjacent to the edge of its attaching face, terminating at the forward end of the shank portion. It should be 70 understood, however, that this strip may be extended rearwardly of that location if desired. The strip 14 of celluloid is preferably cemented to the attaching face of the sole 10. That may be done, for example, by applying pyroxylin cement to the appropriate portion of the surface 75 of the sole 10, letting the cement dry, coating it with a small amount of a suitable softener and moistening the strip of celluloid with a solvent, for example acetone, and applying it in 80 that condition to the sole. The nature of celluloid is such that it is not necessary under these conditions to maintain the sole under pressure for any substantial time. All that is necessary is to apply a relatively light pressure for 85 an instant, as by gently rubbing or pressing manually. Under some circumstances, indeed, it is sufficient merely to moisten the strip of celluloid with a suitable softener and to apply it directly to the outsole without the previous application 90 of cement to the outsole. The operation may be performed in this way if, for example, the sole is to be attached to a shoe by through-and-through stitching, the stitches passing through the strip of celluloid. It should be noted, more- 95 over, that it is not essential that the strip of celluloid be cut exactly to conform to the shape of the forepart of the shoe. The treatment of the celluloid with a softener such as that mentioned above renders it sufficiently flexible so 100 that it can be conformed to the shape of the sole of the shoe without difficulty even though originally it departed substantially from that shape. Thus the strips of celluloid may be died out in only a few different sizes, each size be- 110

ing sufficient to take care of soles of a group of adjacent sizes. Similarly, it is not necessary to die out the strips in different shapes to take care of different soles varying somewhat in shape, for example in width or in the curvature of the toe.

In the manufacture of shoes having cement-attached soles, a coating 16 of pyroxylin cement is applied to the roughened portion of the sole 10 and preferably also to the inner portion of the exposed surface of the strip 14 of celluloid, as illustrated in Figs. 1 and 3. The sole is then cement-attached to a shoe the bottom of which has been roughened and coated with 15 pyroxylin cement as is usual in the manufacture of shoes of that type. After this the shoe with the sole cement attached thereto is removed from the cement sole attaching machine and a heel 20 (Fig. 4) is attached thereto and 20 the edge of the sole trimmed and set in the usual manner. The edge trimming operation removes not only the surplus stock at the edge of the sole but trims off the marginal portion of the strip 14 of celluloid leaving a narrow 25 stripe or band 22 of celluloid adjacent to the shoe upper and terminating at the finished edge 24 of the sole, as shown in Fig. 4.

Various pleasing ornamental effects, desirable particularly for women's novelty shoes, may be 30 attained by the aid of my invention. Thus the stripe of celluloid may take the form of a very narrow band, as will be the case if the edge of the sole is trimmed quite closely. Under such 35 circumstances a pleasing effect can be obtained by using celluloid of a color which contrasts notably with the color of the shoe upper as, for example, a red strip of celluloid contrasting with a black upper; or if the sole is not trimmed so closely a somewhat wider band of color will be 40 produced. Under these circumstances it may be preferred to use celluloid of a color which will contrast less vigorously with the shoe upper as, for example, a light green or medium green strip of celluloid with a dark green shoe upper.

45 Having described my invention, what I claim as new and desire to secure by Letters Patent of the United States is:

1. That improvement in methods of preparing soles for attachment to shoes which comprises 50 preparing an outsole only slightly larger than the size to which it is to be finished in the completed shoe, softening a strip of celluloid and while in its softened condition causing it to adhere to the marginal portion of the attaching face of the sole in conformity with the outline 55 of the sole whereby, when the edge trimming operation is performed on the finished shoe, the sole will be left with a narrow strip of the celluloid visible about the forepart of the sole of 60 the shoe adjoining the shoe upper, and apply-

ing a coat of pyroxylin cement to the inner portion of the attached strip of celluloid as well as to the adjacent portion of the attaching surface of the sole.

2. As an article of manufacture an outsole to be cement attached to a shoe, the sole having a strip of colored celluloid secured to the marginal portion of its attaching face and extending to the edge thereof, and being provided with a coat of pyroxylin cement extending also over at least the inner portion of the strip of celluloid.

3. As an article of manufacture, an outsole to be cement attached to a shoe, the marginal portion of the sole being roughened on its attaching face at its shank and forepart, the sole having a strip of colored celluloid cemented to the marginal portion of its forepart at and adjacent to the edge of its attaching face, and the roughened portion of the sole being provided with a coat of pyroxylin cement extending also over at least the inner portion of the strip of celluloid.

4. That improvement in methods of manufacturing shoes which comprises securing a strip of celluloid to the marginal portion of the attaching face of a sole, applying to the marginal portion of said face of the sole a coat of pyroxylin cement extending over at least the inner portion of the strip of celluloid as well as the adjacent portion of the face of the sole, and attaching the sole to a shoe with said cement.

5. That improvement in methods of manufacturing shoes which comprises roughening the marginal portion of the attaching surface of a sole, securing to the outer portion of the roughened area a strip of celluloid, applying to the marginal portion of said face of the sole a coat of pyroxylin cement extending over at least the inner portion of the strip of celluloid as well as the adjacent roughened portion of the face of the sole, letting the cement dry, and thereafter activating it, applying the sole to a suitably prepared shoe bottom, and holding the shoe and sole under pressure while the cement sets.

6. A shoe having a cement-attached outsole with a strip of colored material upon the marginal portion of the attached face of the outsole extending about the forepart of the shoe, the sole attaching cement adhering to the inner portion of the strip of colored material as well as to the adjacent portion of the attaching face of the sole.

7. A shoe having a strip of celluloid cemented to the marginal portion of the attaching face of its outsole, the outsole being attached to the shoe bottom by pyroxylin cement adhering to the inner portion of the strip of celluloid as well as to the adjacent portion of the attaching face of the outsole.
